CLAIM

The ornamental design for a body scrubber set, as shown and described.

DESCRIPTION

FIG. 1 is a front perspective view of a body scrubber set of my new design;
FIG. 2 is a front plan view thereof;
FIG. 3 is a rear plan view thereof;
FIG. 4 is a left plan view thereof;
FIG. 5 is a right plan view thereof;
FIG. 6 is a top plan view thereof; and,
FIG. 7 is a bottom plan view thereof.
